A. DIEMER,
DISTRIBUTER FOR ELECTRICAL IGNITION SYSTEMS,
APPLICATION FILED MAR. 28, 1913.

1,074,777.

Patented Oct. 7, 1913.

UNITED STATES PATENT OFFICE.

ANTON DIEMER, OF STUTTGART, GERMANY, ASSIGNOR TO THE FIRM OF ROBERT BOSCH, OF STUTTGART, GERMANY.

DISTRIBUTER FOR ELECTRICAL IGNITION SYSTEMS.

1,074,777.

Specification of Letters Patent.

Patented Oct. 7, 1913.

Application filed March 28, 1913. Serial No. 757,332.

To all whom it may concern:

Be it known that I, ANTON DIEMER, a subject of the Emperor of Germany, residing at and whose post-office address is Lerchenstrasse 77, Stuttgart, Germany, have invented certain new and useful Improvements in Distributers for Electrical Ignition Systems; and I do hereby declare the following to be a full, clear, and exact description of the invention, such as will enable others skilled in the art to which it appertains to make and use the same.

The present invention relates to distributors for electrical ignition systems for internal combustion engines, and particularly to one wherein the contact brush or brushes connected to the ignition system and also the contact segment or segments connected to the spark plug or plugs of the engine are normally stationary, while a rotary contact member is arranged to connect the contact brush or brushes with the contact segment or segments in the desired order to effect the desired order of ignition of the combustible mixtures. In its preferred form for a multiple cylinder engine, there is a normally stationary contact segment for each engine cylinder or each spark plug, whereas the rotary contact member is provided with a like number of contact segments arranged to engage the contact brush or brushes, and also provided with a contact brush electrically connected to all the contact segments of the rotary member and adapted to engage the normally-stationary contact segments in order to thereby electrically connect the normally-stationary contact brush or brushes with the normally-stationary contact segments in turn.

As an example of its application, I have shown my distributor embodied in an electrical ignition system for starting and running multiple-cylinder internal combustion engines, wherein there is one normally-stationary contact brush electrically connected to a service magneto driven from the engine together with the rotary part of the distributor for ignition during running, and also a second normally-stationary contact brush angularly displaced from the first and electrically connected to a starting magneto disconnected from the engine so as to be driven independently thereof for starting the engine from rest by ignition. An ignition system of this kind is shown in

United States Patent No. 1014824 of January 16, 1912, in which the distributor comprises a stationary distributor member having insulated segments connected to the spark plugs in the cylinders of the engine, and two angularly-displaced rotary contact brushes insulated from each other and connected to two independent sources of current supply for running and starting ignition, in such manner that the source of supply for starting ignition is connected to the spark plugs in turn in the compression periods of the corresponding pistons, while the source of supply for running ignition is connected to the spark plugs in turn in the working periods of the corresponding pistons.

In the accompanying diagrammatic drawings, illustrating the application of my distributor to an electrical ignition system having an engine-driven service magneto for ignition during running and a starting magneto disconnected from the engine for starting the engine from rest by ignition, as an example, Figure 1 shows the distributor in the position in which the service magneto is connected to one of the spark plugs in a cylinder of a four cylinder engine, as an example; and Fig. 2 shows the position of the distributor in which the starting magneto is connected to the same spark plug.

In the drawings, A is a starting magneto disconnected from the engine so as to be driven independently thereof in any suitable way. One terminal of the primary winding is connected through the mechanical interrupter *a* to the ground, and the other terminal is connected directly to the ground, as shown. One terminal of the secondary winding is grounded while the other terminal is connected through the slip ring *a'* to the normally-stationary contact brush *m*.

The service magneto B is driven from the engine for the purpose of supplying ignition currents during running. The primary winding and the mechanical interrupter *b* are connected as in magneto A, while the secondary winding is connected through the slip ring *b'* to the normally-stationary contact brush *l*. The distributor is provided with a normally-stationary distributor member having the insulated contact segments 1, 2, 3 and 4, which are electrically connected to the insulated electrodes

of the spark plugs K_1 , K_2 , K_3 , and K_4 in the engine cylinders C_1 , C_2 , C_3 and C_4 . The rotary contact member S of the distributor is driven by the engine and comprises the contact segments s_1 , s_2 , s_3 , and s_4 electrically connected together and to the contact brush s , as shown. The contact segments s_1 , s_2 , s_3 and s_4 are arranged to engage the contact brushes m and l in turn, while the contact brush s is arranged to successively engage the distributor segments 1, 2, 3 and 4. In Fig. 1, the brush l is engaged with the contact segment s_3 , and the brush s is engaged with the distributor segment 1, so that at this time the ignition current produced by the service magneto B is conducted to the spark plug K_1 to produce a spark thereat and thereby ignite the combustible gas in the cylinder C_1 . In Fig. 2 the contact brush 20 s is still engaged with the contact segment 1, but the contact segment s_2 is now engaged with the brush m , instead of s_3 and l being in engagement, so that now the starting magneto A is connected to the spark plug 25 1 whereas before the service magneto B was connected thereto. The distributor contacts 1, 2, 3 and 4 are given such a peripheral extent that the contact brush s continually engages each of them during the whole of the 30 two periods in which the brush l engages one of the rotary contact segments and in which the brush m engages the rotary contact segment which is in advance of the other one in the direction of rotation of the distributor. This arrangement provides for the proper connection to the spark plugs irrespective of the advanced or retarded adjustment of the ignition period of the 35 system.

40 The distributor parts are so arranged relatively to the stroke of the engine that at the position shown in Fig. 1, the piston of the cylinder C_1 is in its working stroke, while the service magneto B is arranged to produce its ignition current at this period. Thus the system is effective to bring about ignition of the combustible mixtures in the cylinders in turn in the usual way during running of the engine, the starting magneto 45 A not being driven then and therefore not interfering in any way with the normal operation.

As has been pointed out in the patent referred to, internal combustion engines, on 50 automobiles or in other applications, always tend to stop at such position that the cylinder requiring the next spark to start the engine in the proper direction of rotation is in its compression stroke. Accordingly, 55 the distributor is arranged so that one of the contact segments s_1 , s_2 , s_3 , s_4 , is then in engagement with the contact brush m , while the contact brush s is in engagement with that one of the contact segments 1, 2, 3, 4 60 which is connected to the spark plug in the

cylinder requiring ignition. Therefore, if the starting magneto A be driven when the engine is at rest, the ignition currents produced thereby will be conducted to the proper spark plug and produce a spark 70 thereat to start the engine in the proper direction, provided, of course, that combustible mixture has remained in the cylinder or is pumped therein before or at the time of operating the starting magneto. As soon 75 then as the service magneto B supplies satisfactory ignition sparks, the operation of the starting magneto may be discontinued, the engine then operating in the ordinary way as pointed out above.

It will be understood that any other suitable kind of source of ignition current may be employed instead of the starting magneto A or the service magneto B, or both, and that the distributor herein shown may be used in other ignition systems wherein there is a single source of ignition current instead of the two sources A and B, and a single contact brush instead of the two brushes l and m . Furthermore the distributor shown may be used with an internal combustion engine having one or any other number of cylinders, besides the four cylinders shown.

Having thus described my invention, what I claim is:

1. A distributor for distributing ignition currents to the spark plugs in a multiple-cylinder internal combustion engine comprising a normally-stationary contact brush 100 adapted to be electrically connected to a source of ignition current supply, a normally-stationary distributor member having insulated contact segments adapted to be electrically connected to the spark plugs, 105 and an engine-driven rotary contact member having contact segments arranged to engage the contact brush at different periods and also having a contact brush electrically connected to all the contact segments of the rotary member so as to connect the normally-stationary contact brush with each of the contact segments of the distributor member in turn; substantially as described.

2. In an electric ignition system for internal combustion engines, two independent sources of ignition current supply, two normally-stationary contact brushes insulated from each other and electrically connected to the individual sources of current supply, 110 a normally-stationary contact segment adapted to be electrically connected to a spark plug in a cylinder of the engine, and a rotary contact member adapted to electrically connect the two contact brushes with the contact segment, at different periods; substantially as described.

3. In an electrical ignition system for internal combustion engines, two independent sources of ignition current supply, two nor- 130

normally-stationary contact brushes insulated from each other and electrically connected to the individual sources of current supply, a normally-stationary contact segment adapted to be electrically connected to a spark plug in a cylinder of the engine, a rotary member having contact segments arranged to engage the contact brushes at different periods and also having a contact brush electrically connected to all the contact segments of the rotary member and arranged to engage the normally-stationary contact segment so as to connect the sources of current supply to the spark plug at different periods; substantially as described.

4. In an electrical ignition system for multiple-cylinder internal combustion engines, two independent sources of ignition current supply, two normally-stationary contact brushes insulated from each other and electrically connected to the individual sources of current supply, a normally-stationary distributor member having contact segments insulated from each other and adapted to be electrically connected to spark plugs in the cylinders of the engine, and a rotary contact member adapted to electrically connect at different periods each of the contact brushes with each of the contact segments in turn; substantially as described.

5. In an electrical ignition system for multiple-cylinder internal combustion engines, two independent sources of ignition current supply, two normally-stationary contact brushes insulated from each other and electrically connected to the individual sources of current supply, a normally-stationary distributor member having contact segments insulated from each other and adapted to be electrically connected to spark plugs in the cylinders of the engine, and a rotary member having contact segments arranged to engage the contact brushes at different periods and also having a contact brush electrically connected to all the contact segments of the rotary member and arranged to successively engage the contact segments of the distributor member to thereby connect the individual sources of ignition current supply to the spark plugs at different periods; substantially as described.

6. In an electric ignition system for internal combustion engines, a cylinder having a piston and a spark plug, a source of ignition current supply adapted to produce sparks at the spark plug for starting ignition, an independent source of ignition current supply adapted to produce sparks at the spark plug for running ignition, two normally-stationary contact brushes insulated from each other and electrically connected to the individual sources of current supply, a normally-stationary contact segment adapted to be electrically connected to the spark plug, and a rotary contact member

adapted to electrically connect the contact brushes with the contact segments at different periods, the arrangement being such that the source of current supply for starting ignition is electrically connected to the spark plug to produce a spark thereat when the piston is in its compression stroke, while the source of current supply for running ignition is electrically connected to the spark to produce a spark thereat when the piston is in its working stroke; substantially as described.

7. In an electric ignition system for internal combustion engines, a service magneto driven by the engine for supplying ignition current during running, an independent source of ignition current for supplying ignition current during starting, two normally-stationary contact brushes insulated from each other and electrically connected to the individual sources of current supply, and a normally-stationary contact segment adapted to be electrically connected to a spark plug in a cylinder of the engine, and an engine-driven rotary contact member adapted to electrically connect the contact brushes with the contact segment at different periods to thereby connect the sources of ignition current supply to the spark plug at different periods; substantially as described.

8. In an electric ignition system for internal combustion engines, a service magneto driven by the engine for supplying ignition current during running, a starting magneto adapted to be driven independently of the engine for supplying ignition current during starting, two normally-stationary contact brushes insulated from each other and electrically connected to the individual sources of current supply, a normally-stationary contact segment adapted to be electrically connected to a spark plug in a cylinder of the engine, and an engine-driven rotary member adapted to electrically connect the contact brushes with the contact segment at different periods to thereby connect the sources of ignition current supply to the spark plug at different periods; substantially as described.

9. In an electric ignition system for multiple-cylinder internal combustion engines having pistons and spark plugs, a service magneto driven by the engine for supplying ignition current during running, an independent source for supplying ignition current during starting, two normally-stationary contact brushes insulated from each other and electrically connected to the individual sources of current supply, a normally-stationary distributor member having contact segments insulated from each other and adapted to be electrically connected to spark plugs in the cylinders of the engine, and an engine-driven rotary member having contact segments arranged to engage the

contact brushes at different periods and also having a contact brush electrically connected to all the contact segments of the rotary member and arranged to successively engage 5 the contact segments of the distributor member to thereby connect the individual sources of current supply to the spark plugs at different periods, the arrangement being such that the source of current supply for starting 10 ignition is electrically connected to each spark plug when the corresponding piston is

in its compression stroke, while the source of current supply for running ignition is electrically connected to each spark plug when the corresponding piston is in its working 15 stroke; substantially as described.

In testimony whereof I affix my signature, in presence of two witnesses.

ANTON DIEMER.
